UNITED STATES PATENT OFFICE.

WILLIAM N. FESSENDEN, OF CANDOR, NEW YORK.

FOUNTAIN MARKING-PEN.

SPECIFICATION forming part of Letters Patent No. 555,783, dated March 3, 1896.

Application filed November 21, 1895. Serial No. 569,690. (No model.)

To all whom it may concern:

Be it known that I, WILLIAM N. FESSENDEN, a citizen of the United States, residing at Candor, in the county of Tioga and State of New York, have invented new and useful Improvements in Fountain Marking Implements, of which the following is a specification.

This invention relates to a fountain marking device, and is more especially designed for use in addressing boxes, bales, and packages of merchandise for shipment or the like, and it has for its object to produce a marking implement of the character described wherein the supply of marking fluid to the distributing-point shall be continuous, uniform, and not dependent upon the pressure with which the implement is held in contact with the surface being marked, which shall operate to keep the marking-point perfectly clean and smooth at all times, and prevent the accumulation thereon of dust, dirt, grit and the like, to provide an improved bearing for a marking device having a universal movement, and, finally, to improve, simplify and render more efficient implements of this nature in general.

To these ends my invention consists in the features and in the combination or arrangement of parts hereinafter described and pointed out in the claims following the description, reference being had to the accompanying drawings, forming a part of this specification, wherein—

Figure 1 is a perspective view of my improved marking implement. Fig. 2 is a longitudinal section of the same. Fig. 3 is plan view of the cap 11, looking from the interior; and Fig. 4 is a similar view of the hood 7.

Referring to the drawings, the numeral 1 indicates the reservoir designed to contain the marking fluid, and which also constitutes the handle of the implement, by which it is grasped and held during the operation of marking. As shown, said reservoir or handle consists of a hollow cylinder closed at one end by a cap or stopper 2, and at its opposite end is provided with a ferrule or nipple 3 that terminates in a hollow contracted neck 4. Formed integrally with or secured to the neck 4 is an approximately semispherical hood or casing 5, which at its apex is provided with

a small semispherical or cup-shaped recess 6, in which is adapted to seat a bearing-ball 7. The lower edge of the hood or casing 5 is provided with a laterally-projecting annular flange 8, to which is adapted to be fastened by small bolts or rivets 9 a corresponding flange 10 formed on the upper end of a cup-shaped cap 11. The cap 11 on its under side is formed with a circular aperture 12, through which is adapted to project a spherical marking device 13, and which has a bearing at one point only against the bearing-ball 7 seated in the recess 6 of the hood or casing 5.

Clamped between the flanges 8 and 10 of the hood 7 and cap 11 is an annulus 14, of felt or other suitable pliable material, which is in intimate contact at its inner circumference with the periphery of the marking-sphere 13.

It will be noted that the contracted neck 4 is deflected at an angle relative to the longitudinal axis of the reservoir or handle 1, whereby the said handle may be held in the hand in manner similar to a pen, pencil, or brush, and at the same time bring the exposed portion of the marking-sphere in the correct position to fairly engage the surface to be marked.

The operation of my improved marking implement will be readily understood.

To fill the reservoir or handle the cap or stopper 2 is removed and the marking fluid poured into the reservoir, after which the cap or stopper is replaced. The implement is now ready for instant use without further manipulation. The handle 1 is grasped in the hand in the same manner as a pencil or brush and the exposed portion of the marking-sphere 13 applied in contact to the surface to be marked and is guided over such surface to trace the desired characters thereon. Owing to the marking-sphere 13 having a bearing at one point only against the bearing-ball 7 the implement is moved over the surface being marked with the greatest ease, and owing to the universal movement of said marking-sphere the utmost freedom of movement is afforded to the implement under the guidance of the operator. As the marking-sphere is moved over the surface to be marked the marking fluid, which flows from the reservoir-handle by the contracted neck 4 into the hood 7, comes into intimate contact with the mark-

ing-sphere, and as the latter is rotated by its frictional contact with the surface being marked the felt disk or annulus 14 evenly distributes the marking fluid over said sphere and prevents a surplus quantity thereof from being supplied to that portion of the sphere brought into immediate contact with surface marked, while at the same time said disk or annulus acts as a wiper to remove from the marking-sphere all dust, dirt, and grit and prevent the same from being introduced into the interior of the implement and mixed with the supply of marking fluid.

It will thus be seen that a great economy is effected by preventing an unnecessary supply of the marking fluid being applied to the marking-sphere, that said fluid is kept free from admixture with foreign substances picked up by the marking-sphere, and is applied uniformly and continuously to the marking-sphere, and that the surface of the latter is kept smooth, bright, and clean.

It will also be evident that by means of the disk or annulus described the employment of valves and other similar devices that are both expensive and apt to become clogged and deranged is entirely dispensed with, while the general construction and arrangement of the parts of the implement combine to produce a device possessing high efficiency with great durability and that may be manufactured at slight cost.

I have described the perforated disk or annulus 14 as being constructed of felt or other pliable material; but I wish it to be understood that a variety of materials may be employed for the purpose, as any material that will embrace the marking-sphere yieldingly or with an elastic or pliable contact will fully answer the purposes and perform the functions heretofore described in connection with the perforated disk or annulus.

I have described my improved marking implement as being more especially designed for marking boxes, bales and packages of merchandise; but it will be evident that the same may be employed as a fountain-pen, pencil or marking device for writing, drawing or tracing characters or writings of every kind whatsoever without departing from the spirit of my invention.

Having described my invention, what I claim is—

1. The combination with a handle and reservoir, of a universally-movable marking-sphere carried by said handle, and a flexible

annulus arranged about said marking-sphere and in contact therewith, substantially as described.

2. The combination with a handle and reservoir, of a casing carried thereby and communicating therewith, a universally-movable marking-sphere protruding through said casing, and a flexible annulus arranged within said casing and in contact with the periphery of the marking-sphere, substantially as described.

3. The combination with a handle and reservoir, of a two-part casing carried by the handle, one part of said casing consisting of a hood and the other part an apertured cap, a marking-sphere having a universal bearing in said casing and protruding through the apertured cap, means for securing the two parts of the casing together, and a flexible annulus clamped between the meeting edges of the two parts of said casing and in contact with the periphery of the marking-sphere, substantially as described.

4. The combination with a handle and reservoir, of a casing carried thereby, a universally-movable marking-sphere protruding through said casing, a bearing-ball arranged in a cup-shaped recess formed in the upper portion of said casing and forming a bearing for the marking-sphere, and a flexible annulus arranged within said casing and in contact with the periphery of the marking-sphere, substantially as described.

5. The combination with the handle and reservoir 1 of the contracted neck 4 communicating with one end of said reservoir and handle and carrying the semispherical hood 5 having in its upper portion a cup-shaped recess 6 and provided at its lower edge 95 with a lateral flange 8, an apertured cap 11 provided at its upper edge with a corresponding flange 10, means for securing said flanges together, a universally-movable marking-sphere 13 arranged in said hood and cap and protruding through the latter, a bearing-ball 7 seated in said cup-shaped recess and forming a bearing for the marking-sphere, and a flexible annulus clamped between the flanges 8 and 10, substantially as described.

In testimony whereof I have hereunto set my hand in presence of two subscribing witnesses.

WILLIAM N. FESSENDEN.
